UNITED STATES PATENT OFFICE.

CHARLES W. HAWKS AND GEORGE H. WARREN, OF SHELBOURNE FALLS,
MASSACHUSETTS.

LETTER-FILE.

SPECIFICATION forming part of Letters Patent No. 365,597, dated June 28, 1887.

Application filed August 31, 1883. Serial No. 105,253. (Model.)

To all whom it may concern:

Be it known that we, CHARLES W. HAWKS and GEORGE H. WARREN, both of Shelburne Falls, in the town of Shelburne, in the county of Franklin and State of Massachusetts, have made certain new and useful Improvements in Letter-Files, whereof the following is a specification, reference being had to the accompanying drawings, in which—

10 Figure 1 shows a view in elevation of our letter-file with its cover in the closed position. Fig. 2 shows a vertical section taken through the line $x-x$ of Fig. 1. Fig. 3 shows a punching mechanism attached to the base-board of the file. Fig. 4 shows in elevation the base of the file holding the upright receiver on which letters are placed. Fig. 5 shows a letter or paper punched for filing. Fig. 6 shows in elevation the hinged plate, to which letters are 20 transferred to remove others from underneath them.

The several figures are not drawn to the same scale, but similar letters denote the same parts.

25 Attached to the base-board A is the base B, which is preferably a metallic casting on which is cast the boss a, and in which are two opposite chambers, b b', which hold the hinge-plate C by its projections c c' in bearings d d' in the 30 chambers. The motion of the hinged plate is limited to the play allowed between the sides e e' of one or both the chambers. Into the base B is permanently fastened the stationary plate or "receiver" D, so called because it 35 receives the letters to be filed. The hinged plate C is held up into plate by the flat spring E, which is preferably made of thin sheet spring-steel, and is placed in a seat cast in the base B, and fastened by the rivet a', passing through 40 a hole made in it for the purpose. The end f of the hinged plate works upon the spring E, and the bearings d d' are so located relative to said spring that the part of the plate between the bearings and the spring is in the shortest radial distance from the bearings as a center when 45 said plate is midway between the two positions shown in Fig. 2, whereby when it passes that position the spring aids in driving it toward and holding it in either of said two positions toward which it may be passed.

To the base-board A is also attached a punching mechanism, F, which is made by inserting into the casting G a sheet-metal spring-plate, H, having an opening closely fitting with sharp edges the upright stationary part or punch g, 55 which passes through it when the spring is pressed downward by one of the square corners h or h' on the lever I, or the corresponding corner on said lever on the other side of the part g, one or more of which corners act 60 like cams to depress said spring when said lever is turned in either direction. Said lever I is hinged into the casting G, as shown, and its arm N is serrated with notches i i, &c. The punch g is stationary and has its top constructed with cutting-edges and curved, as shown, whereby when a letter is placed in the punching mechanism between the spring-plates H and l and the lever depressed a shearing-cut, k, is made in it. The upright part and its opening 65 are of such shape as to cut a hole in the letter of such form that when the receiver D enters it fits the same, and by reaction against one or more of the sides of the hole prevents the paper from swaying or sidewise motion 70 and holds it firmly in place.

Underneath the spring H is a supplementary sheet-metal spring, l, which is turned down at its front end and guides the paper over the upright cutter or punch g and into place for 80 punching, the arms m m' of the casting G acting as stops to hold the paper in proper place for punching. The arm N of the lever is held in the upright position shown in Fig. 2 by the reaction of the spring-plate H upon the square 85 face h h'. In Fig. 2 are shown the sheets K in place filed.

To the base-board is attached, by the long spring plates n n', a cover, L. Said springs are made in two parts, which are hinged together 90 at their junction, as shown, and are attached to each of the boards far enough from their junction to allow the cover to be raised a considerable distance above the base-board for the insertion of letters between them, and yet to 95 hold said cover by spring-pressure down upon the letters.

If the arm N be moved forward or backward slightly, it will be replaced by the spring-plate H, acting on its square face h h'. To the lower 100

end of the cover is affixed a metallic plate, *o*, through which (and through the cover, if projecting so far as shown) is an opening, *p*, located in position, when the cover is brought 5 down upon the letters, to strike its front edge upon the inclined face *q* of the arm *N* and drive said arm back slightly and pass down over the similar inclined faces of the notches *i i* until it rests upon the letters, when the spring-plate 10 *H* drives forward the lever-arm *N*, and the plate *o* is caught in one of the notches *i i*, whereby the cover is fastened in place, as by a spring-catch. Through said opening *p* is then passed the arm of a small padlock, *s*, if it is 15 desired to lock the letters from inspection, which prevents the metallic plate *o* from being detached from the notch in which it may be.

The opening or passage in the groove *P*, between the curved edges and side of the receiver *D*, is continued through the base *B*, and may be continued through the base-board, if desired, and is for convenience of passing a string, ribbon, or metallic binder through the papers filed while in place on the receiver to 20 tie or bind them for filing away.

The purposes of the receiver are, first, to hold a paper filed on it from motion of the whole sheet separately from the receiver in any direction in its own plane, and, second, to hold 25 it from rotation in its own plane about the receiver. These purposes may be accomplished with various forms of the receiver and of the perforation in the paper through which it passes. A relative construction of the two 30 elements only is required, which is shown in our device. Thus the first purpose is accomplished by constructing the perforation and the receiver relatively to each other, so that the perforation is large enough to admit the 35 receiver, and when the receiver is in place in it, and the paper is filed thereby, the material at the side or sides of the perforation must fit upon the contour of the cross-section of the receiver taken in the same plane as that of the 40 adjacent paper in place filed upon it, and cover with fitting surface three or more bearing-points on said contour located in position to prevent motion in either direction in the plane of the paper, freedom enough being allowed of 45 course to permit the easy filing and removal of the sheets. Receivers having some forms of contour of the cross-section require bearing-surfaces covering four bearing-points, regular quadrilaterals, for example, requiring one on 50 each side. And the second purpose is accomplished when the paper is on the receiver filed if some part of the contour of the receiver against which the paper at the side of the perforation fits in attempted rotation in either 55 direction is as far away from any given point within the perforation about which as an axis the rotation is attempted as the paper bearing and reacting against it.

Obviously the change from the form in which 60 the bearing-faces are in the same circle must be material to prevent rotation by tearing.

The hinged transfer-plate *C* has a like contour, to prevent rotation out of place of papers thereon. The flat or plate form of the plates *C* and *D* is adopted because it is substantial, 75 cheaply made by punching from sheet metal and striking up the edges, and affords the greatest width for resisting rotation or other motion with the least possible material, and consequently the least possible perforation of the 75 filed papers.

Some files have been made with receivers to hold papers which are filed upon them by the process of passing the receiver through the paper, the perforation being thereby made 80 by the receiver itself, which is sharpened or pointed to penetrate it, of which receivers the cross-section has the required form to prevent rotation when in an aperture fitting them; but this process of making a perforation without 85 a separate punching mechanism often leaves it ragged at the edges, tearing the paper sometimes enough so that the receiver is inoperative to prevent rotation. The addition to the same base-board as part of the operative machine of a punching mechanism adapted to 90 punch a perforation having the relations described to the contour of the cross-section produces better results. In such receivers also which have a suitable form to prevent rotation the necessity of a pointed or sharp end necessarily small to perforate the paper with the expense of constructing an interior passage in the form other than circular while an 95 external groove would be inoperative because 100 the paper would be cut in form to fill it, have rendered impracticable the construction of a longitudinal passage through which to pass the ribbon or binder while the papers are in place filed. But in our file the receiver has a groove, 105 *P*, making a longitudinal passage through the receiver and base combined with the contour of cross-section described, a cross-section of 110 which passage is indicated by the interior edge of the upper end of the receiver and the dotted line connecting the curved edges thereof. The opening in the papers filed will occur if the 115 perforation is larger in some part than the cross-section of the receiver, provided the receiver and perforation are constructed, as described, to prevent motion or rotation of the paper; but it is preferable that it should be protected by the curved edges, as in this case.

Another element of this invention is the construction of the punching mechanism with its 120 notched lever and its attachment to the base-board to provide a spring-catch for the cover.

What we claim as our invention, and for which we pray Letters Patent, is—

1. In a letter-file, the base *B*, mounted on 125 the board *A*, and having attached to it a receiver, *D*, of elongated form, for the filing of sheets of paper by its insertion through perforations thereof, as described, combined with a punch mounted on the same base-board *A*, 130 and adapted, as described, relatively to said receiver as formed to punch in a sheet to be

filed, and a perforation coincident therewith having sides fitting on said inserted receiver at a sufficient number of salient points to prevent rotation of the filed sheet upon the receiver.

5. 2. In a letter-file, the base B, base-board A, punch F, and the receiver D, attached to the base B, and having the longitudinal passage P, all said parts being constructed and arranged to operate substantially as described.

10. 3. A letter-file having a receiver for the filing of letters by its insertion through perforations thereof and attached to a base-board, combined with a cover hinged to the same base-board and a punch adapted to punch said perforations and attached to the same base-board, and having a lever-arm for the purposes of its actuation, notched, as described, against which arm a spring attached to said punch bears, as described, said spring and lever-arm arranged

relatively to said cover and constructed, as 20 described, to act as a spring-catch to engage and hold the cover in place in different positions on the filed letters.

4. In a letter-file, the cover L, hinged to the base-board A, and having attached to it the 25 plate o, having the opening p, combined with the lever I, attached to said base-board, as described, and having the notches i i and the incline q, and with the spring-plate H, also attached to said base-board, as described, all 30 said parts being constructed and arranged substantially as described.

CHARLES W. HAWKS.
GEORGE H. WARREN.
